ADJUSTABLE BOOK END HOLDER

Ernest Oldenbusch, Jr., Rockville Center, N. Y.

Application October 15, 1932. Serial No. 638,015

2 Claims. (Cl. 211—43)

This invention relates to a book holder of the type which may rest or repose on the top of a table, desk or other suitable flat top support.

One of the objects of the invention is the provision of a practical as well as ornamental book holder, which book holder is also variously adjustable for the purpose of holding one or more books.

Another object of the invention is the provision of a device which embodies the feature of an ornamental book-end and which is also capable of holding one or more books; the device being placeable in such a manner as to add to the decorative or artistic appearances in a room.

With the foregoing and other objects in view, the invention resides in the particular combination, constructions and functions of the parts hereinafter fully described and illustrated in the accompanying drawing, in which

Figure 1 is a perspective view of a device embodying the features of the invention;

Figure 2 is a fragmentary longitudinal sectional view through the device;

Figure 3 is a section on the line 3—3 of Figure 2;

Figure 4 is a section on the line 4—4 of Figure 2.

Referring now more particularly to the drawing, it will be apparent that the device includes two end members, an end member 10 and an end member 11. The end member 10 is of ornamental construction and it is to be understood that it may be made in various designs and forms. The end member 10 is made preferably of metal and is of hollow construction. The end member 10 has a base 12 which is open at the bottom and has a transverse inwardly directed portion 13. The end member 11 is in the form of a plate, the same being made of sheet metal, and the lower edge thereof has feet 14 integral therewith, and also an extension 15 integral therewith and which is disposed laterally between the feet 14. A guide 16 extends in a recess in the base portion 13, and is secured to the base in any suitable manner, such as by brazing or soldering. The guide 16 is in the form of a channel and is provided with inwardly directed flanges 17 on the opposite sides of the guide 16. The guide 16 is flush with the bottom surface of the base 12 and extends from the front portion beyond the rear wall of the end member on which the portion 13 is formed. The guide 16 has a longitudinal slot 18 for a purpose to appear hereinafter. The extension 15 has a projection 19.

In order to associate the end member 11 with the end member 10 so that they will be movable toward and away from each other, and also be maintained in alignment, so that the end members 10 and 11 may be variously adjustable with

relation to each other, the extension 15 is slidably received in the guide 16. The end members 10 and 11 are prevented from being separated from each other by the projection 19 encountering the base portion 13. It is to be understood that the projection 19 is bent from the plane of the extension 15 to a vertical position, or one perpendicular to the plane of the extension 15, by the use of a suitable tool which is inserted through the slot 18 after the extension 15 is entered in the guide 16. When the projection 19 has been so disposed the bottom of the base 12 of the end member 10 is closed by pieces of cardboard or the like, 20, and a piece of felt 21. Pieces of felt 22 are also secured to the under sides of the feet 14. The felt pieces 21 and 22 hold the device elevated sufficiently so that the extension 15 and the guide 16 will be up out of contact with the surface on which the holder rests, and these felt pieces also prevent highly polished surfaces from being scratched, as will be understood.

From the foregoing it will be obvious that the end members 10 and 11 may be variously adjusted with relation to each other to hold one or more books; and that the device may be so placed that the end member 11 will be hidden while the ornamental end member 10 will present a decorative or artistic appearance.

I claim:

1. A device of the character described comprising end members adapted to engage therebetween one or more books, one of said members being of ornamental hollow construction and having a recess in the base thereof, a guide channel extending in the recess and secured to said base flush with the bottom surface of the face, a portion of the other of said members being received in said guide channel whereby said members may be variously adjusted with relation to each other, and said portion having upwardly extending means engageable with said base inside of the latter to prevent the separation of the members.

2. A device of the character described comprising end members adapted to engage therebetween one or more books, one of said members having a base provided with a recess in the bottom face thereof, a guide extending in the recess and secured horizontally to said base, said guide consisting of a channel, a horizontal extension on the other one of said members formed from the material thereof which is received in said guide, whereby said end members may be variously adjusted with relation to each other, said extension having a projection integral therewith engageable with said base to prevent the separation of the end members.
